UNITED STATES PATENT OFFICE.

WALTER O. SNELLING, OF PITTSBURGH, PENNSYLVANIA, ASSIGNOR TO CONSOLIDATED LIQUID GAS COMPANY, OF CHICAGO, ILLINOIS, A CORPORATION OF ARIZONA.

GAS PROCESS AND PRODUCT.

1,096,797.

Specification of Letters Patent.

Patented May 12, 1914.

Application filed March 9, 1914. Serial No. 823,505.

To all whom it may concern:

Be it known that I, WALTER O. SNELLING, a citizen of the United States, residing at Pittsburgh, in the county of Allegheny and State of Pennsylvania, have invented new and useful Improvements in Gas Processes and Products, of which the following is a specification.

My invention comprises a new and improved method of storing acetylene; a new composition of matter involving acetylene gas mixed with one or more liquefied hydrocarbon gases of the paraffin or saturated series and possesses among others, the objects and advantages hereinafter stated.

More specifically my invention contemplates the mixing of acetylene gas with one or more liquefied hydrocarbon gases of the paraffin or saturated series whereby the acetylene is stored in a compact, safe, economical and efficient fashion, and whereby a new gaseous product comprising an intimate mixture of acetylene with the hydrocarbon gases is produced.

My invention contemplates the solution of acetylene under pressure in a liquefied natural gas comprising one or more paraffin hydrocarbons held under pressure in liquid form, whereby the solvent escapes with the acetylene and is combustible therewith.

The advantages of the well known high illuminating properties of acetylene are to a large extent offset by the difficulties in handling this extremely explosive product in a safe and economical way. Two methods of storing compressed acetylene have heretofore been discovered, each of which, however, involves numerous disadvantages. According to one of these methods, the acetylene is pumped under high pressure into acetone. In comparison with pure compressed acetylene this solution of acetylene in acetone is less dangerous. This method, however, is open to a serious objection. It is impossible to fill the container entirely full of acetone for the reason that the acetone and acetylene when mixed occupy more space than the acetone itself. Therefore

either at the beginning or at some time during the consumption of the gas from the container, there is a space in the container above the liquid acetone and charged with compressed acetylene which is highly explosive and makes the package dangerous to handle commercially.

Another method and one of wide use, is to first fill the container with some porous absorbent such as, for instance, asbestos or a mixture of charcoal and certain salts, secondly saturate this filling with acetone and then force in acetylene under pressure. If, however, this method is used and the porous absorbent does not completely fill the container, a space is left in which an explosive charge of acetylene gathers with results that may be very serious. Moreover the amount of acetylene which may be stored in this way is very small in comparison with the weight of the package and the package itself is costly on account of the peculiar requirements for its construction. It is never certain that such a package does not contain some rift or pocket in the absorbent in which an explosive charge of acetylene may collect.

In both methods just described, the container must first be charged with acetone or with an absorbent and then with acetone, as the case may be and thereafter charged with acetylene under pressure. When the acetylene is drawn off, the original contents of the container, i. e. acetone or acetone and absorbent, remain and thus it is evident that a given tank does not contain as much fuel as it would if the absorbent of the acetylene were capable itself of being used as a fuel.

It is an object of my invention to obviate the dangers and difficulties inherent in the present methods of using acetylene and to provide a means of storing acetylene in a safe and efficient manner.

It is another object of my invention to provide a gas having high illuminating and fuel properties and without the properties which make acetylene difficult to use.

It is a still further object of my invention

to provide a combustible liquid solvent for acetylene which gasifies and burns with the acetylene.

One form of service tank for storing and transporting my new mixture for use as an illuminant, which may be employed, is shown in the accompanying drawings, though others having proper storage capacity, strength and valve control may be employed, without departing from the spirit of my invention.

In the drawings: Figure 1 is a longitudinal sectional view of a container suitable for use with my product. Fig. 2 is a detail sectional view of a reducing valve which may or may not be used in connection with the container shown in Fig. 1.

In the accompanying drawings, the reference numeral 10 indicates the body of the container into the top of which is secured a metal valve construction 11 having the outlet 12 and the safety device 13 to prevent the tank being disrupted under abnormal conditions. A pipe 14 leads from the lower portion of the metal valve to the bottom of the tank so that the fuel can be taken off constantly from a point at or near the lowest part of the container, as desired.

An ordinary reducing valve 15 shown in Fig. 2 may be attached either to the outlet pipe 12 or other convenient location to provide for releasing the gases under substantially uniform pressure, as desired.

When it is desired to fill the tank with my composition of matter, the hydrocarbon or hydrocarbons may be first injected in the tank through the opening 12 and then the acetylene later forced into it under pressure through the same opening or the hydrocarbons and acetylene may first be mixed and then forced into the tank under pressure through the same opening with substantially the same results, depending upon the convenience to the operator.

I have discovered that acetylene is miscible with or soluble in ethane, propane and butane and any mixture of any two or all three of these hydrocarbons. I have further discovered that if a small portion of the solution thus formed is withdrawn from the container and the pressure is relieved, there is evolved a gas consisting of a mixture of acetylene with the hydrocarbon or hydrocarbons, in the proportions contained in the liquefied mixture, that is to say, these gases vaporize together in the form of an intimate mixture, the composition of which varies according to the liquefied mixture of gases taken. Now by dissolving acetylene in a liquefied gas comprising ethane, propane and butane, or mixtures of any two or all three of these hydrocarbons and holding said liquefied mixture under pressure in a storage tank, and in then withdrawing the

liquefied mixture in minute quantities from the tank and allowing it to vaporize or gasify as withdrawn, I can obtain from a storage tank of suitable construction, a continuous supply of gas having substantially constant and unvarying composition. This gaseous mixture is admirably adapted to the purpose of illumination.

I find that my new mixture of acetylene with ethane, propane and butane, in liquefied form, or with one or more of these hydrocarbons, is entirely free from the explosive properties possessed by compressed acetylene alone. The solvent which I use for acetylene has considerable vapor pressure at ordinary temperature, so that if a container is initially partly filled with this liquid solvent, the space above the liquid before the acetylene is forced in, will be occupied by the vapor of the solvent. When the acetylene is forced into the container, as by allowing it to bubble through the liquid solvent, some of it will rise above the solvent and appear in gaseous form in the space above the liquid partly occupied by the vapor of the solvent. Thus when the container is partly filled with the mixture, there is some liquid and some vapor, but the solvent is associated with the acetylene in both of these conditions. There is no space in the container in which the solvent and the acetylene are separate from one another. Rigorous tests have shown that a mixture of acetylene and the new solvent is not explosive. It is thus not at all necessary that the container for such a mixture should be filled with absorbents such as asbestos or charcoal, as was found necessary in the old tanks previously referred to. Accordingly, tanks filled with acetylene dissolved in one or more of the paraffin hydrocarbons above mentioned, offer not only a perfectly safe means of storing and transporting acetylene, but also enable a greatly increased quantity of acetylene to be stored and transported for a given weight of package.

Since the solvent used by me issues from the container with the acetylene and as these can be burned together, the practice of my invention affords important advantages as follows: First, since there is nothing in the container but fuel, the volume of the fuel in the container is greatly in excess of that which can be safely held in acetylene containers, of the same size under the methods heretofore known. Second, this improvement effects a great reduction in the initial cost of expensive containers, as well as in their interest and depreciation charge per pound of fuel used. Third, transportation charges are materially reduced.

It is to be noted that for every pound of acetylene transported from the point of manufacture to the point of use, many

pounds of container, absorbent and solvent must be transported the same distance and back again. If the solvent itself, as well as the acetylene can be used to supply light or heat, then the cost of transportation will be materially reduced per pound of fuel and, in the case of my invention, this transportation charge will be reduced in three ways, viz: (1) smaller weight of package, due to 10 absence of solid absorbent upon which transportation must be paid for two trips every time the container is filled; (2) since solvent is burned up, its transportation need be paid for only one trip instead of two for each 15 time the container is filled, and (3) since the amount of fuel used is much increased in burning the solvent, as well as the acetylene, the transportation charge will be calculated upon the weight of both acetylene and solvent 20 and thus again greatly reduced.

Various forms of apparatus may be employed in utilizing my new process of storing acetylene under pressure by causing it to be mixed with one or more of the hydrocarbons above described, namely, ethane, propane and butane in liquid form, and I have, therefore, deemed it unnecessary to illustrate and describe more than one form of such apparatus. For instance, the acetylene and the solvent could be mixed together in a large tank provided with some suitable means for stirring or agitating the contents. The tank would first be partly filled with the solvent, and then the acetylene would be forced into the tank until a proper amount had been admitted and absorbed, the contents of the tank being in the meantime kept agitated, so as to insure a uniform mixture. The tank would then be ready for the charging of automobile or other tanks or cylinders. The mixture may also be made in the service tanks. Various other methods of mixing and storing might also be used without departing from the spirit of my invention. 45

Another important advantage involved in my invention is that by it I can produce an illuminating agent having a flame of great brilliancy with a minimum tendency to cause soot when burned from an appropriate jet or tip.

I have specifically mentioned ethane, propane and butane, as illustrative of the hydrocarbons to be employed for the reason that these are the principal hydrocarbons of natural gas which may be liquefied and held in containers under pressure practicable for storage and shipping purposes as liquefied gases, yet which are gaseous at normal temperatures and atmospheric pressure, and these are the compounds which can be procured in great quantity and which have the properties suitable for use as solvents for and to mix with acetylene.

I claim:—

1. The process of storing acetylene under pressure in a suitable container, which consists in first partially filling said container with liquefied hydrocarbon of the paraffin series and then forcing acetylene into said liquefied hydrocarbon and causing the acetylene and said hydrocarbon to become thoroughly mixed. 70

2. The process of storing acetylene under pressure in a suitable container, which consists in first partially filling said container with a mixture of hydrocarbons of the paraffin series held by pressure in liquefied form and then forcing acetylene into said liquefied mixture of hydrocarbons and causing the acetylene and said liquefied hydrocarbons to become thoroughly mixed. 80

3. The process of storing acetylene under pressure in a suitable container, which consists in first partially filling said container with propane, butane and ethane in liquefied form, and then forcing acetylene into the liquefied gas and causing the acetylene and the liquefied gas to become thoroughly mixed. 85

4. The method of storing acetylene under pressure in a suitable container, which consists in first partially filling said container with a mixture of liquefied propane and another hydrocarbon of the paraffin series, and then forcing acetylene into said mixture of hydrocarbons and causing the acetylene and said liquefied hydrocarbons to become thoroughly mixed. 95

5. A closed receptacle containing under pressure a mixture of acetylene and liquefied hydrocarbon of the paraffin series, said hydrocarbon becoming vaporized upon being released from the receptacle and escaping with the acetylene to form a gaseous mixture therewith, and means for controlling the release of the said mixture from its receptacle. 100

6. A closed receptacle containing under pressure a mixture of acetylene and a liquefied hydrocarbon solvent which upon release of pressure becomes vaporized and escapes with the acetylene to form a gaseous mixture therewith. 105

7. As a new article of manufacture, a gas package comprising a holder or tight vessel, a contained charge of one or more of the hydrocarbons of the paraffin series, acetylene mixed with the liquefied hydrocarbon, an outlet for the gas package and means for controlling the outlet whereby acetylene and the liquefied hydrocarbon may be taken off simultaneously from the package to form a uniform gaseous mixture, substantially as set forth. 115

8. In an apparatus for storing and delivering gas, a vessel containing a supersaturated solution of acetylene and one or more

liquefied hydrocarbons of the paraffin series under pressure, an outlet pipe extending into said vessel to the point near the bottom thereof through which the mixture of acetylene and liquefied hydrocarbon may escape or be forced into the vessel, and a valve for controlling the flow of the said mixture into or out of said vessel.

In witness whereof, I hereunto subscribe my name to this specification in the presence 10 of two witnesses.
